(57) **CLAIM**

The ornamental design for an air conditioner cover, as shown.

DESCRIPTION

FIG. 1 is a perspective view of an air conditioner cover showing our new design;

FIG. 2 is a front elevational view thereof;

FIG. 3 is a right side elevational view thereof;

FIG. 4 is a left side elevational view thereof;

FIG. 5 is a rear view thereof;

FIG. 6 is a top view thereof; and,

FIG. 7 is a bottom view thereof.

The broken lines in the drawings illustrate portions of the air conditioner cover which form no part of the claimed design.

1 Claim, 5 Drawing Sheets
